UNITED STATES PATENT OFFICE.

WILLIAM L. HOWLAND, OF MASON CITY, IOWA.

GOLF BAG.

Application filed June 3, 1926. Serial No. 113,503.

This invention relates to carrying cases and has particular reference to certain improvements in golf bags.

Primarily the invention comprehends an improved golf bag structure which functions efficiently to completely enclose and lock the clubs within the same for shipment by transportation companies or for storage of the bag and its contents when not in use, and which further serves when the bag is in use to facilitate the selection and removal of the clubs from the bag by supporting the same in such a manner as to dispose the heads above the upper open end of the bag.

More specifically the invention comprehends a golf bag including a main body portion of preferably lesser length than the shortest club, in which said body is provided with a telescopic bottom section projectable from the lower end of the body a sufficient distance to dispose the head of the longest club below the upper end of the body, and in which the bag structure further comprehends a closure means designed to respectively fit the upper open end when the bottom section is projected outwardly or the lower end when the bottom section is telescoped within the bag body.

Other objects of the invention reside in the comparative simplicity of construction, the economy with which the same may be manufactured, and the general efficiency of the use to which the same may be put.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a vertical sectional view through a golf bag constructed in accordance with the invention and illustrating the arrangement of the same for completely enclosing the clubs;

Fig. 2 is a similar view illustrating the arrangement of the bag for its active use on the "links";

Fig. 3 is a side view of the bag arranged in the manner illustrated in Fig. 1;

Fig. 4 is an enlarged sectional view of the upper end of the bag with the closure in locked condition.

Referring to the drawings by characters of reference, 10 designates the body of the bag which is preferably of cylindrical configuration and open at both its upper and lower ends which are reinforced by identically constructed annular sleeves or collars 11 and 12. The sleeves or collars are each provided with an annular inwardly bent bead 13 which presents a channel in the outer periphery within which the body ends are secured in any suitable manner. The bag structure further includes a bottom section 14 which is of substantially cylindrical formation provided with a closed lower end 15 and having an outwardly projecting marginal rim 16. The diameter of the bottom section 14 is of a size to fit within the inner periphery of the bead 13 of the lower sleeve or collar 12 so as to allow for sliding movement of said section therethrough to permit of telescopic action of the bottom section with respect to the bag body, it being obvious that the rim 16 coacts with the bead 13 of the lower collar 12 to limit the outward movement of the bottom section.

A closure member in the nature of a circular plate 17 having a marginal outwardly flared flange 18, is provided and is of the proper size and configuration to fit within the collars 11 and 12 so that the flange 18 thereof will engage and snugly fit the beads 13 to limit inward movement of the closure. In order to provide means for retaining the closure within the collars, a pair of radially projectable and retractible bolts 19 are mounted on the inner face of the closure plate so that the outer extremities 20 thereof when projected outwardly will engage behind the bead 13 of either collar. Any suitable actuating mechanism may be provided for projecting or retracting the bolts 19, such as a key-actuated lock 21 of any well-known type, the structure of which is not illustrated for the reason that it forms no part of the present invention.

In use and operation, when it is desired to completely enclose or house the clubs in the bag, for transportation to or from the links or for storage of the same, the bottom section 14 is projected outwardly or downwardly until the rim 16 engages with the bead 13 of the lower sleeve 12, as illustrated in

Figs. 1 and 3. Under this arrangement the bag from the bottom wall 15 of the bottom section to its upper end is of sufficient length to accommodate the longest club. This permits the closure plate 17 to be inserted within the upper sleeve 11 and locked in place as illustrated. When the bag is to be used on the links, the closure plate 17 is unlocked and removed from the upper collar 11; the bottom section 14 is telescoped to a position within the lower end of the main body 10, the closure plate 17 being engaged and locked within the lower collar 12, as illustrated in Fig. 2, so that the length of the bag from the bottom wall 15 of the bottom section to the upper end of the upper collar 11 is less than the length of the shortest club, whereby the heads of all the clubs will protrude from the upper end of the bag to facilitate the selection and removal of the clubs.

From the foregoing it will thus be seen that an improvement in golf bags has been devised which is simple, comparatively inexpensive, and efficient both in the active and inactive uses of the bag.

What is claimed is:

1. A golf bag, comprising a body, a telescopic bottom section, and means respectively engageable within the opposite ends of the body to constitute a member for closing the upper end when the bottom section is projected outwardly, and a means for retaining the bottom section against outward movement when telescoped within the body. 35

2. A golf bag, comprising a tubular body section having collars at its upper and lower ends, each collar having an inwardly projecting annular bead, a tubular bottom section having a closed lower end and an external outwardly projecting rim at its upper end adapted to engage with the bead of the lower collar for limiting the outward movement of said bottom section, a closure plate adapted for respective insertion within the 45 collars at the opposite end for engagement with the beads thereof, and means carried by said closure plate for locking engagement with the beads to retain said closure plate in associated relation with the collars, as and 50 for the purpose specified.

WILLIAM L. HOWLAND.
